UNITED STATES PATENT OFFICE.

HENRY POWER, OF MONTREAL, QUEBEC, CANADA, ASSIGNOR OF ONE-HALF TO
WILLIAM HALTON, OF MONTREAL, CANADA.

SANDING DEVICE.

1,352,626.

Specification of Letters Patent. Patented Sept. 14, 1920.

Application filed December 31, 1919. Serial No. 348,564.

To all whom it may concern:

Be it known that I, HENRY POWER, a subject of the King of Great Britain, and citizen of the city of Montreal, in the Province of Quebec, Dominion of Canada, have invented certain new and useful Improvements in Sanding Devices; and I hereby declare that the following is a full, clear, and exact description thereof.

10 Heretofore considerable inconvenience and loss have been experienced in the generation of electric power by the pulley and belt drive connecting an axle of a car with a dynamo, owing to the fact that under certain 15 conditions friction between the pulley and belt is reduced to such an extent that the pulley actually loses its grip on the belt and rotates freely without it. Many attempts have been made to increase the holding 20 power of the belt and pulley by changing the structure of one or the other without avail and my invention is to cure this defect and increase the friction, and thus overcome the slipping between pulley and belt whenever 25 the prevailing conditions require and and particularly during the winter season when snow and ice frequently completely destroy the friction between the pulley and belt.

30 I solve the problem by providing a device which will project sand or other gritty material to the contacting surfaces of pulley and belt. More specifically stated the invention consists of an air nozzle communicating 35 with a chamber, a sand projecting tube being connected to the opposite side of the chamber leading to a convenient point in close proximity with the points of contact between the pulley and belt; the nozzle being preferably adjustable. The air supply 40 is controlled by a manually operated valve and an automatic valve. The sand receptacle is preferably air tight, and the connection between it and the sand delivery tube is 45 preferably a loose one to permit back pressure air to escape without entering the sand box. Another feature of the invention consists of a protection for the ejector from escaped steam from the heating equipment 50 of the car or other damping influences.

For full comprehension however, of my invention, reference must be had to the accompanying drawings in which similar ref-

erence characters indicate the same parts and wherein:

55 Figure 1 illustrates in elevation a portion of the frame of a passenger car equipped with my invention;

Fig. 2 is an enlarged vertical sectional view illustrating the connection between the sand receptacle and delivery tube; and

Fig. 3 is a vertical sectional view of the sand delivery tube and ejector.

The apparatus is designed to produce the desired results with the least practical 65 amount of sand and compressed air, the principle being to use a small stream of sand at relatively high velocity, and this only when additional friction between pulley and belt is known to be necessary. This 70 reduces the wear of the belt and pulley to a minimum. In fact it is reasonable to believe that it actually saves wear as compared with continued slipping of the pulley within the belt.

75 Compressed air is used in an economical manner by passing same through a discharge nozzle 10 designed to produce high velocity, this requiring a minimum amount 80 to produce the desired results. The operation being controlled manually or by an electrically operated automatic control valve. For manual control of the sand an operating cock 12 is placed in the vicinity of the switch panel (as indicated in Fig. 1) 85 so that trainmen when holding the operating cock open may have a view of the voltmeter, and as soon as the voltmeter indicates that the dynamo is generating, the operating cock may be allowed to close, thus shutting off the application of sand. The electrically operated automatic control valve 2 employed by me is preferably of the type 90 commonly used on the cars of electric railways for signaling, the valve stem constituting the armature of a solenoid (not shown). This solenoid is included in an electric circuit 70 and is magnetized by current generated by the dynamo. To secure an intermittent operation of the valve a 100 "make and break" device 71 is included in the circuit 70. The automatic valve may be disconnected from the dynamo by a switch 72.

105 The apparatus for supplying the sand to the contacting surfaces of the pulley and

belt comprises a box 14 to contain the sand or other comparatively dry gritty substance referred to hereafter as "sand." The sand box is fitted with a comparatively tight cover 15 adapted to be held against displacement by the vibration of the car or other causes, and it may be any desired shape and located in any convenient place on the car or may be sunk in the floor or placed underneath the car floor. It is preferable, but not absolutely necessary, that the bottom of the box be inclined toward the outlet tube so as to discharge all of the contents by gravity. The lower end of the neck 20 enters loosely into the upper end of the sand delivery tube 21 which is sufficiently larger to provide an outlet for upwardly flowing air due to back pressure in the ejector and caused by stoppage of the sand projecting tube, or other cause. The free escape of this back pressure air prevents air pressure accumulating in the sand box and straining it and possibly scattering its contents. This emergency air outlet is to take care of the first impulse due to the deflection of the air, but this is not sufficient to compensate for sustained blockage. To obviate the continued leakage of the back-pressure air a swinging check valve 25 is located in the delivery tube 21 and adapted to remain open under normal conditions of operation and automatically close when there is a continued flow of sand and air or air alone in the reverse direction.

35 The ejector is attached to the lower end of the tube 21 and consists of ejector body 30 presenting a T-chamber to receive the sand delivered through the tube by gravity. One end of the ejector body is connected to a tube 32 for projecting the sand against the contact surfaces of the belt and pulley. The opposite end of the ejector body is fitted with a bushing 33 in which is screwed the adjustable nozzle 10. The end of this nozzle through which the air is discharged is disposed near the inner end of the sand-projecting tube so that only a small amount of sand flows by gravity in front of the nozzle. The exact position of the nozzle 50 may be adjusted however by screwing it into, or out of, the ejector body, and when correctly adjusted it is secured by means of a lock nut 35 screwed tightly against the end of the ejector body. The air discharge opening may be straight or cone shaped, and of such proportions as to produce the maximum velocity. In operation the discharge of air from the nozzle into the projector tube will tend to produce a vacuum which assists 60 gravity in bringing down sand where it will be thrown or drawn into the projecting tube.

65 The projecting tube extends from the ejector to a point within the space inclosed by the pulleys and belt, and preferably is di-

rected toward the center of the pulley, in such a manner that regardless of direction of rotation of the driving pulley the sand will be quickly carried to the belt where it will produce increased friction to overcome 70 the undesired slipping.

The nozzle 10 is connected to the air pipe line 50 by a combined nut and swivel 51. The adjacent portion of the nozzle being of increased diameter to receive a strainer 53 75 which prevents the sand lodging within the pipe line.

To provide for normal movement of car trucks relative to the car body, the sand-projecting tube is supported, from the car body only, by any convenient arrangement of hangers or braces indicated at 40. This tube is preferably placed to one side of the top line of the belt, and passes it at an angle so that the end of the tube will be directed 85 as nearly as possible to the center of the pulley.

In order to protect the ejector from the dampness of the atmosphere beneath the car, due to escaping steam or other causes, an 90 insulated box 60 of either metal or wood incloses the same and the bushing 30 of the nozzle is fitted into one side thereof permitting the nozzle to be adjusted without disturbing the connections between the box 95 and the ejector body or opening the box, and without disturbing the filler with which the box is packed to protect the ejector.

What I claim is as follows:—

1. In railway passenger car equipment the 100 combination with an axle, a dynamo, a pulley on the axle, a belt looped around the pulley, and an operative connection therebetween and the dynamo, of means for supplying sand to the contacting surfaces of 105 the pulley and belt, consisting of a receptacle for sand; an ejector, a sand delivering tube connecting the sand receptacle to the ejector, an air nozzle with its discharge within the ejector, a sand projecting tube 110 leading from the ejector at a point in alignment with the nozzle to a point in close proximity with the contacting surfaces of the pulley and belt; and means whereby compressed air is supplied to the nozzle. 115

2. In railway passenger car equipment the combination with an axle, a dynamo, a pulley on the axle, a belt looped around the pulley and operative connection therebetween and the dynamo, means for supplying sand to the contacting surfaces of the pulley and belt, said means consisting of a receptacle for sand; an ejector, a sand delivering tube connecting the sand receptacle to the ejector, a check valve within said tube, an air nozzle with its discharge within the ejector, a sand projecting tube leading from the ejector at a point in alignment with the nozzle to a point in close proximity with the contacting surfaces of the pulley and 130

belt; and means whereby compressed air is supplied to the nozzle, the connection between the sand box and sand delivering tube being loose to permit the escape of back pressure air.

3. In railway passenger car equipment the combination with an axle, a dynamo, a pulley on the axle, and a belt looped around the pulley and an operative connection there-between and the dynamo, means for supplying sand to the contacting surfaces of the pulley and belt, said means consisting of a receptacle for sand; an ejector, a sand delivering tube connecting the sand receptacle 15 to the ejector, an air nozzle with its discharge within the ejector, a sand projecting tube leading from the ejector at a point in alinement with the nozzle to a point in close proximity with the contacting surfaces of 20 the pulley and belt; and means whereby compressed air is supplied to the nozzle, an adjustable connection between the nozzle and ejector.

4. In railway passenger car equipment the combination with an axle, a dynamo, a pulley on the axle, and a belt looped around the pulley and an operative connection there-between and the dynamo, means for supplying sand to the contacting surfaces of 25 the pulley and belt consisting of a receptacle for sand; an ejector, a sand delivering tube connecting the sand receptacle to the ejector, a screw threaded bushing within the neck of 30

the ejector, an air nozzle adjustably mounted within the bushing with its discharge 35 within the ejector, and adapted to supply compressed air thereto, a sand projecting tube leading from the ejector at a point in alinement with the nozzle to a point in close proximity with the contacting surfaces of 40 the pulley and belt.

5. In railway passenger car equipment the combination with an axle, a dynamo, a pulley on the axle, and a belt looped around the pulley and an operative connection 45 there-between and the dynamo, means for supplying sand to the contacting surfaces of the pulley and belt consisting of a receptacle for sand; an ejector, a sand delivering tube connecting the sand receptacle to 50 the ejector, an air nozzle with its discharge within the ejector, a sand projecting tube leading from the ejector at a point in alinement with the nozzle to a point in close proximity with the contacting surfaces of 55 the pulley and belt; and means whereby compressed air is supplied to the nozzle and an insulating box inclosing the ejector and associated parts.

In testimony whereof I have signed my 60 name to this specification in the presence of two witnesses.

HENRY POWER.
